US00D811366S

(12) **United States Design Patent** (10) Patent No.: **US D811,366 S**
 Mackiewicz et al. (45) Date of Patent: ** Feb. 27, 2018

(54) **WEARABLE AUDIO COMPONENT**

(71) Applicant: **Harman International Industries, Incorporated**, Northridge, CA (US)
 (72) Inventors: **Damian Mackiewicz**, Shenzhen (CN); **Rafal Czaniecki**, Shenzhen (CN); **Ondrej Vaclavik**, Shenzhen (CN); **Jinwon Yook**, Shenzhen (CN)

(73) Assignee: **Harman International Industries, Incorporated**, Northridge, CA (US)

(**) Term: **15 Years**

(21) Appl. No.: **29/576,143**

(22) Filed: **Aug. 31, 2016**

(51) LOC (11) Cl. **14-01**

(52) U.S. Cl.

USPC **D14/205**

(58) **Field of Classification Search**

USPC D14/205; D29/112; 2/209; 379/430, 379/431; 381/380, 381, 323, 151, 141;

455/90.3, 575.1, 569.1; 5/632; D6/596

CPC H04R 1/1066; H04R 1/1016; H04R 1/10;

H04R 25/00; H04R 1/102; H04R 1/1091

(74) Attorney, Agent, or Firm — Plumsea Law Group, LLC

(57) **CLAIM**

The ornamental design for a wearable audio component, as shown and described.

DESCRIPTION

FIG. 1 is a perspective view of a wearable audio component showing our new design;

FIG. 2 is another perspective view thereof;

FIG. 3 is a front elevation view thereof;

FIG. 4 is a rear elevation view thereof;

FIG. 5 is a side elevation view of one side thereof;

FIG. 6 is a side elevation view of the opposite side thereof;

FIG. 7 is a top plan view thereof; and,

FIG. 8 is a bottom plan view thereof.

The broken lines and unshaded areas form no part of the claimed design.

1 Claim, 8 Drawing Sheets
